UNITED STATES PATENT OFFICE.

DUFF S. ALLEN, OF ST. LOUIS, MISSOURI.

NEEDLE.

Application filed April 17, 1922. Serial No. 554,120.

This invention relates to needles. The present application is a continuation of application Ser. No. 437,803 filed January 17, 1922, as to the subject matter disclosed 5 therein.

One of the objects of this invention is to provide a needle to which the strand can be readily attached and which, when in position, will be securely held.

10 Another object is to provide a needle which is devoid of projecting parts so as to avoid catching of the needle during its passage with the attached strand.

Further objects will appear from the 15 detail description taken in connection with the accompanying drawing, in which:

Figure 1 is an edge elevation of the heel of a needle embodying this invention;

Figure 2 is a side elevation;

20 Figure 3 is a similar view showing the needle partially threaded;

Figure 4 is a similar view showing the needle completely threaded;

Figure 5 is a view similar to Figure 2, but 25 showing another embodiment of this invention;

Figure 6 is a similar view showing the needle threaded; and

Figure 7 is a section on line 7—7, Figures 30 2 and 5.

Referring to the accompanying drawing, 1 designates the needle body which, as usual, comprises a shank having at one end a point and at its other end a heel 2 to which the 35 thread is adapted to be attached. The shank may be either round or oblong in cross-section, depending upon the uses for which the needle is intended. When used as a surgical needle, it is usually oblong in section. The 40 needle body or shank may furthermore be either straight or curved, as is usual in various types of needles.

The heel 2 is provided with an eye 3 which may taper towards the heel tip. This heel tip 45 is split to form a pair of sections 4 having overlapping parts 5. Each of these overlapping parts tapers to an edge 6, and these parts are rounded and extend upwardly to provide horns. They may also be recessed as shown at 50 7 to receive the strand 8, as hereinafter described. The sections or legs 4 are arranged to form a second eye 9 which can taper away from the heel and towards the eye 3, while the heel between the eyes may further be longitudinally recessed as shown at 10 to receive 55 the strand.

In the practical operation of this needle, the strand 8 (which may be a suture when the needle is employed as a surgical needle) is passed through the eye 3, and one of the ends of the strand is then passed into the eye 9 as shown in Figure 3 by forcing it into the tapering recess formed between the edge 6 and the adjacent side of the opposite leg or section 4. The other end of the strand can 60 then be similarly forced into the eye 9. When the strand is thus in position, as shown in Figure 4, the ends of the strand will have been forced into the eye 9 causing the legs to spread apart and as the heel, as well as the 65 needle itself, is of resilient material, these legs will close up and yieldingly engage the strand so as to securely clamp it in position. When the strand is thus in position, the ends thereof will lie in the recesses 10 and 7, thereby 70 avoiding all projections, while the horns or overlapping portions 5 will serve to prevent disengagement and accidental opening of the eye 9. The eye 3 performs the function of providing additional holding means 75 for the strand, especially when in wet or slippery condition, as is usually the case in surgical sutures, for this strand will be wedged into the wedge-shaped portion of the eye, and thus serve as an additional holding 80 means. When it is desired to disengage the strand from the needle, this can be accomplished by reversing the operation, as the strand ends can again be removed from the eye 9 by forcing the strand into the wedge-shaped recesses between the horn of one leg 85 and the adjoining face of the other leg.

In Figures 5 and 6, the eye 3 has been omitted, but the construction is otherwise like that shown in Figures 1 to 4 inclusive. 90 The application of the strand to this needle will be obvious, and it will be noted that when the strand is in position, the bight of it will be securely clamped between the overlapping legs, while the horns 5 again act as 95 guards to prevent accidental disengagement of the strand from the eye, until it is desired to remove it, when the unthreading can be accomplished in the same manner as previously described.

100 It will thus be seen that the invention accomplishes its objects. The needle is simple in construction but effective in its action. It can be readily threaded and unthreaded, so that the tedious operations usually required for threading are avoided. At the same time, the strand is securely held in position so as 105 110

to prevent accidental disengagement. Moreover all projecting parts are avoided, so that tearing and catching during the passage of the needle are entirely avoided. This needle 5 is especially adapted as a surgical needle for the reason that the threading operations can be accomplished with great facility, thereby reducing the time of the operation which is extremely important. Furthermore tearing 10 and lacerating of the wound by passage of the needle is really avoided.

It is obvious that various changes may be made in details of construction without departing from the spirit of this invention; it 15 is, therefore, to be understood that this invention is not to be limited to the specific details described and shown.

Having thus described the invention, what is claimed is:

- 20 1. A needle having a narrow eye at its heel, said eye tapering toward the point of the needle and having resilient portions adapted to clamp a strand therein, and a second eye between said first eye and the point of the needle.
- 25 2. A needle having an eye at its heel, and a second eye adjacent said first eye and between it and the point of the needle, said first eye being tapered toward said second eye and having resilient portions, whereby a strand passing through both eyes when pulled through said second eye will be clamped in said first eye.
- 30 3. A needle, the heel of which is resilient and divided to provide resilient sections forming together a narrow expandible and contractible eye, the terminals of said sections being formed to spread apart sufficiently to permit entrance into said eye of a strand, said sections being adapted to clamp the strand so inserted in said eye, and the needle having a second eye tapering toward said first eye and adapted to bind the strand therein.
- 35 4. A surgical needle provided with an eye, said eye having resilient side portions, a second eye between said first eye and the point of the needle and tapering toward said first eye, said second eye forming a wedging socket and said first eye forming a clamping socket adapted to hold the strand, said needle having thread receiving grooves extending between said eyes.
- 40 5. A needle having a narrow eye open at its heel end and having resilient side portions spaced closely enough together to clamp

a strand therewithin, and a second eye between said first eye and the point of the needle.

6. A needle having a narrow eye at its heel, said eye tapering toward the point of the needle, and having resilient portions 60 adapted to clamp a strand therein, and a second eye between said first eye and the point of the needle, said needle having thread receiving grooves extending between said eyes.

7. A needle having a narrow eye open at its heel end and having resilient side portions spaced closely enough together to clamp a strand therewithin, and a second eye between said first eye and the point of the 70 needle, said needle having thread receiving grooves extending between said eyes.

8. A needle, the heel of which is resilient and divided to provide resilient sections forming together a narrow expandible and contractible eye, the terminals of said sections being formed to spread apart sufficiently to permit entrance into said eye of a strand, said sections being adapted to clamp the strand so inserted in said eye, and the needle having a second eye tapering toward said first eye and adapted to bind the strand therein, said needle having thread receiving grooves extending between said eyes.

9. A surgical needle provided with an eye, 85 said eye having resilient side portions, a second eye between said first eye and the point of the needle and tapering toward said first eye, said second eye forming a wedging socket and said first eye forming a clamping 90 socket adapted to hold the strand, said needle having thread receiving grooves extending between said eyes.

10. A needle having a narrow eye at its heel, said eye tapering toward the point of the needle, and having resilient portions adapted to clamp a strand therein, and a second eye between said first eye and the point of the needle, said needle having thread receiving grooves extending between said eyes, and from said first mentioned eye, along the heel of the needle, whereby the needle and thread will present a substantially smooth exterior.

In testimony whereof I affix my signature 105 this 23rd day of December, 1921.

DUFF S. ALLEN.
